DESIGN FOR AN X-RAY HAND CONTROL

Edward B. Graves, Fort Mitchell, Ky.

Application November 27, 1934, Serial No. 54,182

Term of patent 7 years

To all whom it may concern:

Be it known that I, Edward B. Graves, a citizen of the United States, residing at Fort Mitchell, in the county of Kenton and State of Kentucky, have invented a new, original, and ornamental Design for an X-Ray Hand Control, of which the following is a specification, reference being had to the accompanying drawing, forming part thereof.

Figure 1 is a front elevation of the hand control showing my new design. Figure 2 is a side elevation.

I claim:

The ornamental design for an X-ray hand control, substantially as shown.

In testimony whereof I affix my signature.

EDWARD B. GRAVES.
